CORSET, GIRdle, AND THE LIKE

Mario Laguzzi, West Haven, Conn., assignor to
The Strouse Adler Company, New Haven,
Conn., a corporation of Connecticut

Application November 15, 1935, Serial No. 49,867

5 Claims.

(Cl. 2-37)

This invention relates to an improvement in corsets, girdles or similar articles commonly called "foundation garments."

In such garments it is desirable frequently that the central back portion or section of the garment extending from at least the neighborhood of the waist or small of the back downwardly, be made of non-elastic material, or at least of material that is substantially non-elastic in the vertical direction. Bones or other stays may be used in this back section. Also, it is desirable frequently that side sections of such garments from about the waist to the lower end of the garment be made of material that is elastic circumferentially of the wearer's body in order to tightly confine the garment to the person in a yielding manner, and customarily garters are attached to the lower edge of the garment. Garments so constructed tend to rise on the wearer's person, however.

I have found that this tendency of such garments to rise can be substantially eliminated with a minimum of unsightly seaming of the garment and with other various constructional advantages, by using at the side edges of the central back section, from say the neighborhood of the waist to or near to the lower end of the garment, material that is elastic in the vertical direction, and at the lower end of the garment extending the vertically elastic pieces more or less under the center section; the back garters are attached to this vertically elastic material. Preferably for the purpose indicated, I use for the side circumferentially-elastic sections of the garment, a material that has two-way stretch; that is to say, a material that is elastic in two directions, e. g., vertically as well as circumferentially of the body, and I incline the side edges of the central section toward each other at their lower ends, as by providing the lower ends of these elastic side sections with substantially triangular extensions reaching under the central section, the lower end of the latter being appropriately cut away to fit the triangular sections; this permits each side section and its projecting elastic portion to be made of a single integral piece of material. Further, regardless of whether or not back garters are attached to the elastic material, the provision of the side-wise stretchable material below the non-elastic central back section increases the circumferential elasticity of the lower end of the garment, which I believe to be desirable.

The accompanying drawing illustrates the

form of the invention which I prefer at present. In this drawing:

Fig. 1 is a rear view of a corset, girdle or the like illustrating this invention, partially broken away;

Fig. 2 is a sectional view on the line 2-2 of Fig. 1; and

Fig. 3 is a sectional view on the line 3-3 of Fig. 1.

The garment in a general way is of usual construction and may have a front section 10 extending above the upper edge of the garment to form a brassière. The side sections 11 and 12 are formed from woven material containing rubber, capable of being stretched in two directions. These side sections extend from at least substantially the waist of the wearer to substantially the lower edge of the garment and are connected to the inner back section 13. This back section 13 extends below the waist as shown, and may be provided with vertically-arranged stays 14 and 15, arranged in pockets 16 and 17 attached to the inner back section 13, and the side edges at the lower end extend toward the center line of the back from some distance above the lower edge of the garment, e. g. taper toward each other.

Adjacent portions or projections 18 and 19 of the side sections are correspondingly beveled, so that the lower edges of the side sections extend under the lower end of the back and each side section is attached to the back section throughout the length of the back section below the waist as shown, and is located between the back section and the lower edge of the garment as well as at the side of the back section. Overlying the inner part 13 of the back section is an outer back or facing 20 of non-elastic material. This outer facing covers the stays illustrated so that the presence of the stays will not be evident beneath an outer garment.

Attached to the lower edges of the projections 18 and 19 of the side sections are hose supporters 21 and 22, and strain upon the hose supporters at these points is relieved by the elasticity of the inwardly-projecting portions 18 and 19 of the side sections, and, furthermore, these projections provide additional elastic material to permit stretching horizontally. It will also be understood that additional hose supporters are attached at different points at the lower edge of the garment.

This construction provides a rigid back section and elastic side sections, which side sections stretch horizontally or vertically so as to com-

fortably yield with the movements of the wearer and conform to the contour of the wearer.

The invention may be carried out in other specific ways than that herein set forth without departing from the spirit and essential characteristics of the invention, and the present embodiment is, therefore, to be considered in all respects as illustrative and not restrictive, and all changes coming within the meaning and 10 equivalency range of the appended claims are intended to be embraced therein.

I claim:

- 15 1. A garment of the class specified having a back section of material substantially non-elastic in the vertical direction extending below the waist and the edge of which, at its lower portion, from both sides of it and from some distance above the lower edge of the garment, extends toward the centerline of the back, and a 20 section of material, elastic in the vertical direction, at each side of said back section and extending from substantially the waist of the wearer to the lower edge of the garment and attached to the edge of said back section at both 25 sides of and throughout the length of said back section below the waist, thereby having portions located between said back section and the lower edge of the garment as well as at both sides of said back section.
- 30 2. A garment of the class specified having a back section of material substantially non-elastic in the vertical direction extending below the waist and the edge of which, at its lower portion, from both sides of it and from some distance above the lower edge of the garment, extends toward the centerline of the back, a section of material, elastic in the vertical direction, at each side of said back section and extending from substantially the waist of the wearer to the 35 lower edge of the garment and attached to the edge of said back section at both sides of and throughout the length of said back section below the waist, thereby having portions located between said back section and the lower edge of the garment as well as at both sides of said back section, and hose supporters connected to substantially the lower edges of said elastic sections 40 45

at substantially the portions thereof that are located between the back section and the lower edge of the garment.

3. A garment of the class specified having a back section of material substantially non-elastic in the vertical direction extending below the waist and the edge of which, at its lower portion, from both sides of it and from some distance above the lower edge of the garment, extends toward the centerline of the back, and an integral elastic side section, stretchable in two directions, at each side of said back section and extending from substantially the waist of the wearer to the lower edge of the garment and attached to the edge of said back section at both 15 sides of and throughout the length of said back section below the waist, thereby having portions located between said back section and the lower edge of the garment as well as at both sides of said back section. 20

4. A garment of the class specified, comprising a back section formed of non-elastic material and the lower side edges of which are inclined toward each other, and elastic side sections stretchable in two directions and provided with triangular projections extending rearwardly and along said inclined side edges of the back section, said side sections being attached to the side edges of the back section at both sides of and throughout substantially the length of the 30 back section below the waist. 25

5. A garment of the class specified, comprising a back section formed of non-elastic material and the lower side edges of which are inclined toward each other, elastic side sections 35 stretchable in two directions and provided with triangular projections extending rearwardly and along said inclined side edges of the back section, said side sections being attached to the side edges of the back section at both sides of and throughout substantially the length of the 40 back section below the waist, and hose supporters connected to substantially the lower edges of said elastic side sections at substantially said 45 triangular projections thereof. 45
